[57] CLAIM

The ornamental design for a plaque, as shown and described.

DESCRIPTION

FIG. 1 is a perspective view of the plaque, showing the new design;

FIG. 2 is a top elevational view thereof, the bottom being identical;

FIG. 3 is a side elevational view thereof, the opposite side being identical;

FIG. 4 is a back elevational view thereof;

FIG. 5 is a front elevational view of a second embodiment of FIG. 1, the difference residing in the arrangement of the circular recesses and the inclusion of legible matter in the lower rectangular recess; and,

FIG. 6 is a front elevational view of a third embodiment of FIG. 1, the difference residing in the arrangement of the circular recesses and the inclusion of legible matter in the lower rectangular recess.
